[57] CLAIM

The ornamental design for a tape cassette case, as shown and described.

DESCRIPTION

FIG. 1 is a perspective view of a tape cassette case showing my new design, with the cover raised; FIG. 2 is a left side elevational view thereof; and FIG. 3 is a top plan view thereof. The bottom and rear surfaces that are hidden in FIG. 1 are plain.

FIG.1

FIG. 2

FIG.3
